UNITED STATES PATENT OFFICE.

WALTER SCOTT, OF PLAINFIELD, NEW JERSEY.

PAPER DELIVERING AND FOLDING MACHINE.

SPECIFICATION forming part of Letters Patent No. 240,554, dated April 26, 1881.

Application filed May 10, 1880. (No model.)

To all whom it may concern:

Be it known that I, WALTER SCOTT, of Plainfield, in the county of Union and State of New Jersey, have invented certain new and useful Improvements in Paper Delivering and Folding Machines, which are fully described in the following specification, reference being had to the accompanying drawings, in which—

Figure 1 represents a plan view of a machine embodying my improvements; Fig. 2, a front-side elevation of the same; Fig. 3, a longitudinal vertical section taken on the line $x-x$, Fig. 1; Fig. 4, a detail view, showing a portion of one of the blast-pipes for deflecting the sheets; Fig. 5, a transverse vertical section taken on the line $y-y$, Fig. 1; and Fig. 6 a detail vertical section of the sheet deflecting and imposing mechanism on an enlarged scale.

My invention relates principally to mechanism whereby the sheets are separated after passing the cutting-cylinders, and are gathered or collected so as to be delivered two or more in a single pack to the folding mechanism.

The invention consists in special devices and combinations of devices for effecting these results, all of which will be hereinafter fully described, and the special improvements pointed out definitely in the claims.

In the drawings, A represents the main or supporting frame, which may be an extension to the main frame of the printing mechanism, it being understood, of course, that the mechanism herein described and shown is to be used in connection with printing mechanism, although I have not shown in the drawings any of the printing-cylinders, as the printing mechanism constitutes no part of my present invention, and its arrangement relative to the cutting-cylinders, which are here shown, will be readily understood by those familiar with machines of this description.

The cutting-cylinders, which are usually considered a part of the printing mechanism, are shown in the drawings, being represented by B and B' at the front end of the machine, the former of which is a cutter-cylinder, and is provided with two perforating-blades, b, arranged opposite to each other, and the latter is a corresponding grooved cylinder, and is provided with the usual cutting-grooves b' for the reception of the blades. This cylinder in

the drawings is shown four times the size of the blade-cylinder, and consequently is provided with four cutting-grooves.

Two cylinders, C and D, are arranged in the same horizontal plane some distance in rear of the cutting-cylinder. These cylinders are of the same size, and in circumference are intended to be equal to the length of the sheets of paper plus the distance between the individual sheets after separation. The front cylinder, C, is provided with a series of shallow grooves, c, running around it, and below triangular-shaped guides E are arranged in the space between the two cylinders. The front edge of these guides just enters the grooves in the cylinder C, while the rear edge is a little distance from the surface of the cylinder D, leaving sufficient room for the sheet to run between it and the cylinder. These guides are shown in the drawings mounted on a rod, e, though they may be supported in any other suitable manner.

A pair of tape-rollers, F and G, are arranged just below the rollers C and D, the bite of the latter being in about the same vertical plane as that of the former.

A series of upper tapes, H, are arranged to run around a tape-roller, h, just in rear of the cutter-cylinder; thence to the front tape-roller, F, under and around which they pass to the cylinder C, over which they are carried, and down between the cylinders C and D, passing underneath and back around the latter up over the tape-roller h'; thence to and around roller h'', at the rear upper part of the main frame; thence they pass upward and forward over a roller, h³, and under a roller, h⁴, in the upper part of the frame to the roller h. A similar series of lower tapes, I, is arranged to run around a tape-roller, i, just below the roller h; thence to the roller F, underneath which they pass up between it and the roller G, over the latter, to and around the rear of the cylinder D, up over the roller h', to and around the roller h'', just below the roller h'; thence they run forward and downward over the roller i', and underneath the rollers i³ and i⁴, arranged in the front part of the main frame, to the front roller, i.

To accommodate the folding mechanism, which is arranged at the rear of the machine,

as hereinafter described, the central tapes of both sets are given a somewhat different path, so as not to pass back over the rollers h^2 i^2 at the extreme rear end of the machine. The two 5 upper central tapes, H' , after leaving the roller h' , are carried under and around the roller h^5 , arranged just above and only a short distance in rear of the roller h' . Thence they pass upward over the roller h^3 , and afterward follow 10 the same path as the outside tapes, H . The central lower tapes, I' , after leaving the roller h' , pass to and down around the back of the roller i^5 , arranged a little distance in rear of the former. Thence they pass down to and 15 underneath the roller i^2 , from which point they take the same path as the outer tapes, I . Obviously this arrangement will leave an open space at the rear of the machine between the outer sets of tapes. In this open space is arranged 20 the mechanism for making the first fold in the sheets. In the drawings this mechanism is illustrated by the vibrating creaser J , operating in connection with two ordinary folding-rollers, j ; but this is only for illustration, as any known folding devices may be used 25 for this purpose.

A blast-pipe, K , is arranged a little below the cylinder C and forward of the shaft of the latter. A similar pipe, L , is arranged in the 30 same horizontal plane a little below the cylinder D and in rear of its shaft. These pipes are provided with a series of apertures, k and l , opening inward or toward each other, respectively, and arranged lengthwise of the pipes. 35 These pipes run across the machine, and at one end are journaled in suitable bearings in the side frame, beyond which they project slightly, and are provided at their extremities with short crank-arms k' and l' . At the other 40 side of the machine the pipes project also through bearings in the frame, and are connected by a screw-joint to the upper ends of elbows M , into the lower ends of which are inserted the ends of pipes m , which extend 45 downward and join at the forward end of the pipe n , leading from the blower N . It will be seen, therefore, that the pipes K and L may be turned slightly in their bearings, the screw-connection between them and the elbows permitting 50 this movement without uncoupling. Just inside of these pipes are fixed bars o , in which are inserted a series of short horizontal pipes, P , corresponding to the apertures in the pipes K and L , and extending inward toward 55 each other over the shafts of the tape-rollers F and G . On the outside of these bars are seats O , fitting the pipes, and arranged opposite the apertures therein. These seats are also provided with apertures leading to the 60 short pipes P , as shown in Fig. 6 of the drawings; but by turning either of the pipes K and L slightly, the apertures in them will be closed by being brought against the solid portion of the seats, thereby shutting off communication 65 between these pipes and the short pipes P . The latter pipes do not quite meet,

but open toward each other just above the bite of the rollers F and G , so as to direct a blast of air toward the space between these rollers above their bite, as shown in Fig. 6 of the drawings. Their inner ends should be beveled or cut away slightly on their upper sides so as not to project above the surface of the rollers, and thereby interfere with the passage of the sheets.

A shaft, Q , extends along the back side of the machine, and on this are mounted two cams, R R' , which are provided with cam-grooves r r' , and are arranged relatively to the blast-pipes, so that the outer ends of the 80 crank-arms k' l' enter the grooves r r' , respectively. Obviously, the rotation of the shaft Q , with the cams upon it, will vibrate these crank-arms, and thereby oscillate the blast-pipes K and L , and the cam-grooves are so arranged that the vibration of the respective crank-arms will alternate, so that when one of the blast-pipes is turned to shut off the blast the other will be in position to register with its set of pipes P , to permit the blast of 90 air to issue from the latter.

A paste-fountain, S , is shown in the drawings, mounted on a rock-shaft, s , and provided with the ordinary pasting-disk s' , these parts being arranged so that the disk will be about 95 underneath the tape-roller F , and is brought in contact therewith by a vibration of the fountain, which is effected by any suitable means.

In the drawings, the lever s^2 is attached to 100 the rock-shaft, and is operated by a cam on one of the driving-shafts, which works against the free end of the lever. The pasting-disk is also rotated positively by suitable gearing. These parts of the mechanism are, however, 105 all well known, and do not require a description in detail.

The pasting device is arranged centrally with reference to the roller F , so that when brought into contact therewith it will lay a line 110 of paste along the middle of the sheet passing underneath the roller at that time; and as it is intended to lay this line of paste along the sheet which is then carried up over the cylinder C , the latter should be cut away slightly 115 to correspond, so that no paste will be deposited on its surface.

By referring to Fig. 5 of the drawings it will be seen that one of the grooves, c , in the surface of the cylinder C is in the same vertical plane with the pasting-disk, and therefore accomplishes the object above mentioned.

Two gear-wheels, T T' , are mounted on the end of the drive-shaft, at the front side of the machine, the former of which, on the outer end 125 of the shaft, is a little larger than the latter, as shown in Figs. 2 and 5 of the drawings. The cutting-cylinders are driven from the smaller of these wheels, and the rest of the mechanism from the larger, from which it is 130 apparent that the movement of the delivery and folding mechanism is a little faster than

that of the cutting-cylinders, and the roller F will have this relative motion as compared with that of the cutting-cylinders. The delivery and folding mechanism is driven from the wheel 5 T by means of an intermediate gear-wheel, U, which engages with a gear-wheel, V, on a transverse driving-shaft, the wheel V also driving a train of suitable gearing, which communicates motion to the several cylinders and tape- 10 rollers wherever required. A gear-wheel, V', is also mounted on the same shaft with V, outside of the latter, and is half the diameter of the former. The wheel U is made removable from its shaft, and on the upper side of the wheel 15 V is another shaft, W, adapted to receive the wheel V in such position as to engage with the smaller wheel V', and also with the driving-wheel T. Obviously, under this new arrangement of gearing, the delivery and folding mech- 20 anism will be driven twice as fast as before, while the motion of the cutting-cylinders remains the same.

I have not described in detail the construction and arrangement of all the gearing be- 25 longing to the machine, as that will be readily understood from the drawings and the description below of the operation of the several devices, it being understood, of course, that the gearing and all other devices for moving any 30 of the parts must be so constructed, arranged, and timed relatively as to produce the movements described below, and at the required times.

The directions in which the carrying-tapes 35 and main cylinders, rollers, and gear-wheels move are indicated by arrows in the drawings, so that the course of the sheets of paper will be readily seen.

The operation of this mechanism is as fol- 40 lows: The printed web of paper is run in from the impression-cylinders to the printing-machine between the cutting-cylinders, by which it is perforated along the lines of required di- 45 vision to separate the web into sheets; thence the leading end is delivered to the tapes H and I, by which it is carried along to the roller F, where it is nipped between the lower tapes and the rollers, thereby separating the sheet by reason of the more rapid movement of said 50 roller. Now, suppose the several parts to be in position represented in Figs. 3 and 6 of the drawings. The leading end of the separated sheet is carried up between the rollers F and G, and as the rear pipe, L, is in position to per- 55 mit air to pass out through its series of pipes P, obviously the blast will be directed against the leading end of the sheet, thereby deflecting it forward so that it will be carried by the upper tapes to and around the cylinder C, the 60 blast being shut off at this time from the front set of pipes. As the sheet is carried down underneath the tapes between the cylinders C and D, the guides E direct it to the rear. In the mean time the following sheet has been 65 carried up between the rollers F and G, and the blast-pipes have been shifted so that the

air issues from pipe K and its set of pipes P, while it is shut off from the rear pipes. Ob- 70 viously, the leading end of the second sheet will thus be deflected to the rear and be carried by the lower set of tapes toward the cylinder D. Now, the cylinder C being in circumfer- 75 ence, as stated above, about equal to the length of the sheet plus the distance between the sheets after separation, or, in other words, as this cylinder is geared to make one revolution for each sheet perforated by the cutting-cyl- 80 inders, it is evident that the leading end of the second sheet will join the leading end of the first sheet just as it passes out from the guides E, and the united ends of the two sheets will be carried together into the tapes H and I, under the cylinder D, and thence up over the cylinder at the rear, the two sheets thereby being placed one above the other, in 85 which condition, as a single signature, they are carried up and back by the tapes over the folding-rollers in proper position for the operation of the creasing-blade.

When the pasting device is employed its movement is timed so that a line of paste will be laid along the under side of the first sheet, and therefore when the two sheets are joined the second or lower sheet will be pasted to the first. It will thus be seen that with this mech- 90 anism I am enabled to make up two sheets into a single signature, preparatory to folding, without the use of collecting-cylinders or any other similar devices, the mechanism above described being adapted to a paper of eight 95 pages. For papers of more pages changes must be made in the construction of the mech- 100 anism to adapt it to form a signature containing more sheets.

Now, it is sometimes desired to print a paper 105 of half the size, or a single sheet, upon the same machine, and in order to permit this to be done I have made the provision for chang- 110 ing the speed of the delivery and folding mechanism. Obviously, when the transmitting-wheel U is changed to the front so that the delivery and folding mechanism will be driven at twice the speed as before, the sheets will be separated a distance equal to a little more than the length of one sheet, and therefore the 115 deflecting device by which one sheet is carried around the cylinder C will operate when no paper is passing by it, and the sheet will run through one to the other around the cylinder D and be carried singly to the folder. With 120 this arrangement for changing the speed the machine is adapted to double or single sheet papers without removing or changing any of the remaining devices.

Some other deflecting device may be substi- 125 tuted for the blast mechanism, and obviously some of the devices, especially those for im- parting the required movement, may be changed or others substituted therefor without affecting the principle of operation, and there- 130 fore I do not wish to be understood as limit- ing my improvements to the precise construc-

tion and arrangement of all the parts herein shown and described.

Having thus described my invention, what I claim as new, and desire to secure by Letters 5 Patent, is—

1. The cylinders C D, in combination with the carrying-tapes and a deflecting mechanism arranged to operate alternately to turn one sheet in one direction and the next in the opposite direction, whereby the sheets are made into a single signature, substantially as described.

2. The cylinders C D, having a circumference about equal to the length of a sheet plus the distance between separate sheets, in combination with the upper and lower tapes, the rollers F G, the guides E, and deflecting mechanism operating alternately to turn succeeding sheets in opposite directions, substantially as described.

3. The upper and lower conveying-tapes, in combination with the rollers F G, the blast-pipes K, L, and P, the cylinders C D, and mechanism whereby the blast is alternately shut off from one set of pipes and permitted to issue through the other, substantially as described.

4. The single blast-pipes K and L, mounted in journal-bearings and connected at their open ends directly to their respective feed-pipes by a joint which permits them to be oscillated without disconnecting, substantially as and for the purpose set forth.

5. The blast-pipes K L, mounted in journal-bearings and provided with crank-arms at their closed ends, in combination with the cams R' and delivery-pipes P, substantially as described.

6. The oscillating blast-pipes, in combination with the supporting-bars O, seats o, and delivery-pipes P, substantially as described.

7. The upper and lower carrying-tapes, in combination with the rollers F G, a deflecting device operating alternately to turn the sheets in opposite directions, the cylinders C D, and a folding mechanism whereby two successive sheets are made into a single signature and thus conveyed to the folder, substantially as described.

8. The carrying-tapes, in connection with the rollers F and G, a pasting device arranged to run in contact with the roller F at required intervals, a sheet-deflecting device, and the cylinders C D, all constructed and arranged to operate substantially as described.

9. The cutting-cylinders, in combination with the sheet gathering and delivering mechanism, the gear-wheels V and V', the latter half the size of the former, the removable wheel U, provided with shafts on opposite sides of the wheels V V', and the gear-wheel T, substantially as described.

WALTER SCOTT.
